Primary Examiner — Darcey E Gottschalk(74) *Attorney, Agent, or Firm* — The Small Patent Law Group LLC; Philip S. Hof(57) **CLAIM**

The ornamental design for a power connector, as shown and described.

DESCRIPTION

FIG. 1 is a rear perspective view of a power connector showing my new design;

FIG. 2 is a rear perspective view thereof;

FIG. 3 is a front elevation view thereof;

FIG. 4 is a rear elevation view thereof;

FIG. 5 is a top view thereof;

FIG. 6 is a bottom view thereof;

FIG. 7 is a right side elevation view thereof; and,

FIG. 8 is a left side elevation view thereof.

The broken line showings of FIGS. 1-8 are environmental only and not part of the claimed design.
